(57) **CLAIM**

The ornamental design for a computer enclosure, as shown and described.

DESCRIPTION

FIG. 1 is a front, top, side perspective view of the computer enclosure of the present invention;

FIG. 2 is a front, bottom, side perspective view thereof;

FIG. 3 is a front view thereof;

FIG. 4 is a rear view thereof;

FIG. 5 is a right side view thereof;

FIG. 6 is a left side view thereof;

FIG. 7 is a back, top, side perspective view thereof; and,

FIG. 8 is a back, bottom, side perspective view thereof.

The broken lines shown in the drawings represent portions of the computer enclosure and form no part of the claimed design.
